DESIGN FOR A COMBINED PYROPHORIC LIGHTER AND CIGARETTE CONTAINER

Louis V. Aronson, Newark, N. J., assignor to Art
Metal Works, Inc., a corporation of New Jersey

Application August 13, 1935, Serial No. 58,101

Term of patent 7 years

To all whom it may concern:

Be it known that I, Louis V. Aronson, a citizen of the United States, residing at Newark, in the county of Essex and State of New Jersey, have invented a new, original, and ornamental Design for a Combined Pyrophoric Lighter and Cigarette Container, of which the following is a specification, reference being had to the accompanying drawing, forming part thereof, wherein:

Figure 1 is a rear elevational view of a com-

bined pyrophoric lighter and cigarette container, showing my new design; Fig. 2 is a front elevational view; Figs. 3 and 4 are elevational views of opposite respective sides; and Fig. 5 is a plan view.

I claim:

The ornamental design for a combined pyrophoric lighter and cigarette container substantially as shown.

LOUIS V. ARONSON.
